UNITED STATES PATENT OFFICE.

JOHN MANDER, OF PHILADELPHIA, PENNSYLVANIA.

TUBULAR GAS WATER-HEATER.

SPECIFICATION forming part of Letters Patent No. 639,417, dated December 19, 1899.

Application filed June 16, 1899. Serial No. 720,743. (No model.)

To all whom it may concern:

Be it known that I, JOHN MANDER, a citizen of the United States, residing in the city and county of Philadelphia, State of Pennsylvania, have invented a new and useful Improvement in Tubular Gas Water-Heaters, which improvement is fully set forth in the following specification and accompanying drawings.

10 My invention consists of an improved construction of a tubular gas water-heater to be used in connection with the water-heater of a stove or range, as will be hereinafter more fully set forth, and particularly pointed out 15 in the claim.

Figure 1 represents a vertical sectional view of a tubular gas water-heater embodying my invention. Fig. 2 represents a vertical sectional view of a heater similar to that shown 20 in Fig. 1, but supplied with a plurality of flues or passages for the heating medium, and showing also a boiler and the water-back to which the heater is applicable. Fig. 3 represents a section on line $x-x$, Fig. 2.

25 Similar letters of reference indicate corresponding parts in the figures.

Referring to the drawings, in Fig. 1, A designates a heater, the same consisting of a base portion B, which is provided with the lower 30 convex or dished plate or tube-sheet C, against which the gas-flames from the heating device D are adapted to impinge, said heater being located so that all the heat units impinge upon the under surface of said convex 35 plate and are conducted upwardly through the flue D to the exit, the outlet of said flue being controlled by means of a damper E.

F designates the outer wall or casing of the heater, the same being preferably of an- 40 nular contour to correspond with the contour of the flue D and having connected to its lower portion the base B, which latter is dome-shaped and provided with the pipe G^X.

H designates a pipe leading from the cas- 45 ing F to the water-back H' of the stove or range, while the upper portion of the casing F is provided with a connection J, which leads to the boiler K.

In the construction seen in Fig. 2 I have 50 shown the gas water-heater as provided with a plurality of upwardly-extending flues,

which are here designated as L, said flues leading upwardly from the convex plate C, which corresponds to the similarly-located plate seen in Fig. 1 and adapted to receive 55 heat from the gas-burner D, to the upper plate M, above which is the flue N, which contains the damper E. The number of flues L may, of course, be increased or diminished accord- 60 ing to requirements and are inclosed by a casing F, substantially similar to the casing seen in Fig. 1. The lower portion B of the heater seen in Fig. 2 is substantially the same as that of the heater seen in Fig. 1, and the pipe G and the outlet-pipes J and H for mak- 65 ing the necessary connections to the boiler K and the water-back of the range are all sub- stantially the same as seen in Fig. 1.

In practice I prefer to mount the heater seen in Fig. 2 upon a frame or legs M^X, whereby 70 the heater is effectively supported.

It will be seen that the convex plate C is heated to a high degree by the gas-flames of the burner D impinging directly thereupon, the water in its heated condition passing up- 75 wardly into the boiler K, while by the proper manipulation of the damper D the heat can be retained within the flue or flues D or L as long as may be desired.

The tubular gas water-heater can be used 80 alone, as seen in Fig. 1. The pipe G^X serves as the inlet-pipe, in which case the feed-water is discharged direct on the highly-heated dished plate C, it being understood that the pipe H in Fig. 1 is not employed while the 85 heated water from the heater flows outwardly through the pipe J. When the heater is used in connection with the water-heater of a stove, the pipe H serves as the inlet, as shown in Fig. 2, and the pipe G^X of Fig. 1 or pipe G of 90 Fig. 2 may then serve as a blow-off or a water- outlet from the water-chamber formed by the casing F. In the latter case the water is drawn from the heater in a highly-heated condition direct from the convex surface of the plate C, 95 and since the flames from the burner impinge directly against said plate C it is obvious that the water drawn directly from such close proximity is very hot. The heater can be used equally well with an upright boiler as 100 with the range shown, or it can be used alone, if desired.

In practice I provide an inlet-pipe P for the purpose of conducting water to the boiler K, the water passing therefrom downwardly through the pipe Q into the water-back H' and 5 passing thence through the pipe H into the heater and flowing from the latter through the pipe J into the boiler, the heated water flowing therefrom through the pipe R to the point of supply.

- 10 A heater constructed in accordance with my invention can be quickly set up without necessitating the employment of skilled labor and when in position will require but little attention.
- 15 It will further be apparent that changes may be made by those skilled in the art which will come within the scope of my invention, and I do not, therefore, desire to be limited in every instance to the exact construction I 20 have herein shown and described.

Having thus described my invention, what

I claim as new, and desire to secure by Letters Patent, is—

The combination with a water-heating device of a stove or range, an upper boiler, and 25 a pipe connecting the lower portion of said boiler with the lower portion of said heating device, of a gas water-heater consisting of a casing having an enlarged base portion and an upwardly-extending flue, said base portion 30 having a convex lower plate, a burner situated below said plate whereby the flames therefrom impinge directly upon said plate, a pipe connecting the upper end of said casing with the upper portion of the boiler, and an 35 outlet-pipe leading from the side of the base portion close to said plate, whereby the water is drawn off in a highly-heated condition.

JOHN MANDER.
